UNITED STATES PATENT OFFICE.

MARSHALL DOWNEY, OF HENRY, ILLINOIS.

CURTAIN-DISPLAY CABINET.

No. 815,078.

Specification of Letters Patent.

Patented March 13, 1906.

Application filed May 23, 1905. Serial No. 261,833.

To all whom it may concern:

Be it known that I, MARSHALL DOWNEY, a citizen of the United States of America, residing at Henry, in the county of Marshall and 5 State of Illinois, have invented new and useful Improvements in Curtain-Display Cabinets, of which the following is a specification.

This invention relates to curtain-display cabinets designed especially for use in stores 10 to display lace curtains or the like, and has for its objects to produce a simple inexpensive device of this character which in practice will normally house the curtains to protect them from dust, one from which the curtains may 15 be readily fed for display, and one from which the curtains may be quickly removed when circumstances require.

A further object of the invention is to provide a device of this character, including a rotary curtain-carrying drum, which will be normally locked against movement, one in which the drum may be readily released and manipulated for winding or unwinding the curtains, and one in which one of the drum-operating elements serves as a means for closing and locking the door of the casing in 25 closed position.

A further object of the invention is to provide a device of this character in which the drum is provided with clamping devices for securing the curtains in place, one in which the clamping devices may be readily manipulated for releasing the curtains, and one wherein the drum will be balanced to permit 35 its ready manipulation.

With these and other objects in view the invention comprises the novel features of construction and combination of parts more fully hereinafter described.

40 In the accompanying drawings, Figure 1 is a front elevation of a device embodying the invention and showing the casing in closed position. Fig. 2 is a similar view showing the casing open and a curtain withdrawn for display. Fig. 3 is an end elevation of the device with the parts in the position shown in Fig. 1. Fig. 4 is a vertical cross-section, on an enlarged scale, taken on the line 4-4 of Fig. 1. Fig. 5 is a similar view taken on the line 5-5 of Fig. 1. Fig. 6 is a front sectional elevation, the section being taken centrally and longitudinally through the casing. Fig. 7 is a vertical cross-section, on an enlarged scale, taken on the line 7-7 of Fig. 6. Fig. 8 is a 45 front elevation of the curtain-receiving drum removed from the casing.

Referring to the drawings, 1 designates a casing preferably of octagonal form in cross-section and having a removable section or cover 2 and a hinged gravity-opening door 3, provided at its outer free edge with a slot or recess 4, said casing including in its organization end members or heads 5, provided on their inner faces with upwardly-opening U-shaped bearings 6 and attached to arms or hangers 7, in turn connected by cross-braces 8 and pivotally suspended from a suitable overhead support.

Arranged for rotation in the casing 1 and having end journals 9, seated in the bearings 6, is a reel or drum 10, comprising heads 11 and longitudinally-extending diametrically-opposed plates or webs 12, terminating at their outer edges in right-angularly-disposed bearing members or plates 13, there being 70 carried by each of the webs 12 adjacent to its inner edge a plurality of retaining members or pins 14, disposed at right angles to the surface plane of the web and designed for engagement by the inner ends of spacing-sheets 15, of any suitable pliable material, arranged between the adjacent faces of the curtains 16. Pivoted to each of the webs at a point suitably remote from its outer edge and respectively adjacent its opposite ends is a pair of 85 clamping members 17, each consisting of a pair of sections or links 18 19, pivotally connected at 20 and normally maintained in clamping position by a spring 21, attached at one end to the adjacent web and engaged at 90 its other end with the link 18 at a point near the pivot 20, there being provided on the free end of each link 19 a substantially semispherical bearing-head 22, it being noted in this connection that the clamping members 17, 95 carried by one of the webs 12, extend to and bear upon the face of the next adjacent web, the heads 22 serving, in conjunction with the bearing-plates 13, for removably clamping the curtains 16 in position upon the drum. It 100 may be mentioned in this connection that in order to release the curtains the clamping members 17 are moved outward against the action of springs 21 until the heads 22 are free of the bearing members 13, during which 105 operation the links 18 and 19 will break joint at their pivotal point 20, and, furthermore, that the separating-sheets 15 are permanently retained by the pins 14 to permit removal of the curtains without removing said 110 sheets.

Attached at one end to and wound upon

one of the journals 9 at the outer face of the adjacent head 11 is a spring 23, terminating at its other end in an engaging portion of finger 24, designed to seat loosely in a clip 25, 5 carried by the casing 1, the function of this spring being to balance the curtain-carrying reel and permit its ready manipulation, while at the other end of the drum 10 there is provided an auxiliary drum or spool 26, engaged 10 by one end of a flexible operating element or cord 27, threaded through an opening 28 in the casing and adapted to hang within convenient reach of the operator, there being provided at the lower end of the element a 15 handle 29 and at a point suitably remote from the handle a stop 30 for a purpose which will presently appear. The cord 27, which is adapted to wind upon the spool 26, is arranged for travel upon a guide-roller 31, situated adjacent the opening 28, and is passed 20 around and for travel upon a second guide-roller 32, carried by one end of a brake member or lever 33, pivoted at a point adjacent its longitudinal center and adapted to normally bear at its other end upon the adjacent 25 drum-head 11, the brake being maintained in frictional engagement with said head by means of a spring 34, the tension of which may be regulated by a screw 35. It may be stated that as the cord 27 is wound upon the 30 spool the stop 30, which is of greater size than the opening 28, will contact with the casing, and thus obviate liability of the entire cord being wound upon the spool.

35 Extended around the drum 10 at a point adjacent its longitudinal center is a flexible operating element or cord 36, having one of its ends attached in any suitable manner to one of the webs 12, said cord being adapted 40 to pass through the opening 4 in the door and normally depend from the casing, there being provided on the cord a stop member or ball 37, situated at a point suitably remote from the free end of the cord, which is equipped 45 with a handpiece 38. It is to be particularly noted in this connection that when the cord 36 is wound upon the reel it serves, owing to engagement of the stop 37 with the door 3, to maintain the latter in closed position.

50 In practice the curtains are normally wound upon the reel 10 and housed within the casing, under which conditions the door 3 will be maintained in closed position by means of the cord 36 and its stop, as heretofore explained, while the cord 27 will be in 55 unwound condition and will hang downward, as seen in Fig. 1, while the brake 33 will frictionally engage the head 11 for holding the drum against rotation. Under these conditions the cord 36 will be wound upon the drum, and if it be desired to display the curtains the handpiece 38 is grasped and drawn downward, thereby releasing the door 3 and 60 rotating the reel 10 in a direction for unroll-

ing the curtains and permitting them to hang downward through the opening in the casing, as illustrated in Fig. 2, while at the same time the cord 27 will be wound upon spool 26. When it is again desired to wind the curtains 70 upon the reel, the handpiece 29 is grasped and drawn downward, thereby unwinding the cord 27 from spool 26 and at the same time winding the curtains and cord 36 upon the reel, as will be readily understood, it being noted that as the cord 36 is wound it is drawn over into the slot 4, to thus carry the door 3 to closed position. As the cord 27 is unwound from the reel it will exert traction 75 upon the free end of brake-lever 33 for releasing the bearing end of the latter from the head 11 to permit free rotation of the reel. The reel 10 may be readily removed from its casing to permit attachment of the curtains thereto by removing the section or cover 2 of 80 the casing, it being understood that when the reel is removed from the casing the finger 24 of the balancing-spring will unseat readily from the clip 25.

85 From the foregoing it is apparent that I produce a simple device admirably adapted for the attainment of the ends in view, it being understood that minor changes in the details herein set forth may be resorted to without departing from the spirit of the invention.

Having thus described my invention, what I claim is—

1. In a device of the class described, a casing, a drum journaled for rotation therein, a flexible operating element for rotating the drum in one direction, and a brake for the drum adapted for movement by said drum-operating element to release the drum.

2. In a device of the class described, a casing, a drum journaled for rotation therein, flexible elements designed for rotating the drum in relative reverse directions, and a brake acting upon the drum for normally holding the same against movement, said 105 brake being movable by one of the drum-operating elements to release the drum.

3. In a device of the class described, a casing, a drum journaled for rotation therein, a flexible element designed for rotating the 115 drum in one direction, a pivoted brake member, and a spring for maintaining said member normally in engagement with the drum, said brake being movable by said drum-operating element to release the drum.

4. In a device of the class described, a casing having a hinged door designed to open by gravity, a drum journaled for rotation in the casing, an operating element for rotating the drum, and a stop member carried by the element for engagement with the door to maintain the same in closed position.

5. In a device of the class described, a casing having an opening, a drum rotatively mounted in the casing, means for detachably 125

securing sheets of material to the drum, the latter being designed to normally stand at rest with the sheets wound thereon and the sheets being adapted, when the drum is rotated in one direction, to pass outward through the opening for display, and manually-operated means for rotating the drum.

6. In a device of the class described, a rotary drum comprising in its organization a plurality of webs, means for sustaining the drum, means for rotating the latter, and a clamping member connected with one of the webs and adapted to bear on a second web for clamping a sheet of material thereto, said member comprising a pair of pivotally-connected sections and a spring action on said sections for maintaining the member in clamping position.

7. In a device of the class described, a rotary drum, means for sustaining the same, a pivoted brake member designed to normally engage the drum, said member being provided with a guide and a flexible operating element for rotating the drum in one direction, said element being arranged to travel on said guide and maintain the brake in non-

engagement with the drum during rotation of the latter by the element.

8. In a device of the class described, a casing, a curtain-receiving drum rotatively mounted therein, retaining members carried by the drum for holding spacing-sheets entered between the curtains, and clamping members for maintaining the curtains detachably in position upon the drum.

9. In a device of the class described, a casing, a curtain-receiving drum rotatively mounted therein, a pivoted brake member designed for engagement with the drum to secure the latter against movement, and a pair of flexible operating elements designed to be alternately wound in reverse directions upon the drum, one of said drum-operating elements being operatively engaged with and adapted to operate the brake to release the drum.

In testimony whereof I affix my signature in presence of two witnesses.
